Ever-Dry Laboratories Inc., Los Angeles, Calif.,
a corporation of Nevada

Application July 14, 1932, Serial No. 622,441

12 Claims. (Cl. 128—269)

My invention relates to swabs. Although many aspects of my invention are not restricted to such use, it is more particularly concerned with bottle cap-carried swabs of the type normally stored within the contents of the bottle. In the specific embodiment herein described, the swab is used for applying an anti-perspirant astringent such as an aluminium or zinc chloride preparation, to which certain features of my invention are particularly applicable.

One object of my invention is a swab wherein the porous material may be secured to the supporting stem without cementing or gluing and without the necessity of additional securing parts and preferably also wherein the porous material is non-rotatably secured to the stem.

Another object of my invention is an absorbent element for the swab of considerable length and preferably cylindrical which may take advantage of the manufacturing economies of the use of sheet stock of a thickness considerably less than the length of the swab.

A further feature of my invention is that the cylindrical swab is compressed longitudinally, but still transversely of the grain of the felt, in such a manner that the liquid absorbing interstices tend in general to extend in a plane which is at a normal to the longitudinal axis of the swab.

Other phases of my invention are concerned with the absorbent material used for the swab, the material used for the stem, and the mounting of the stem.

The foregoing, together with further objects, features and advantages of my invention are set forth in the following description of a specific embodiment thereof, illustrated in the accompanying drawing, wherein:

Fig. 1 is a front elevation of a bottle of liquid preparation within which the swab of my invention is shown;

Fig. 2 is an "exploded" perspective view of the parts constituting the swab unit prior to assembly;

Fig. 3 shows in cross section the swab-forming felt washers positioned upon the stem but before compression to final position;

Fig. 4 is a similar view but showing the swab washers compressed to final position and showing in cross section the handle-forming cap mounted on the opposite end of the stem; and

Fig. 5 is a transverse section taken on the line 5—5 of Fig. 2 showing the arrangement of the bars.

In Fig. 1 I have shown a bottle 10 having an externally threaded neck 11 for the reception of a closure cap 12 internally threaded at 13 as

shown in Fig. 4. The bore 14 of a downwardly projecting central boss 15 of the cap 12 receives and mounts the reduced end of a stem 16, the opposite end of which carries a swab element 17. The swab element 17, the stem 16, and the cap 12 constitute the swab unit. The cap 12 forms a handle for the swab when in use and a support for the swab when stored in the bottle.

For the swab element 17, I prefer to use a plurality of felt discs 18 of considerable thickness but still of considerable less normal thickness than the over-all length of the completed swab element 17. This avoids the greater manufacturing expense of cutting cylindrical plugs from thick sheets of felt as would be necessary if the swab were of one piece but of comparable length. It also permits the use of felt stock of a more standard thickness.

Each felt disc 18 is formed with a small circular bore 19 by means of which the discs—or washers—are threaded on to the stem over its upper end and pushed down against the head or button 20 at the lower end of the stem, as shown in Fig. 3. The stem 16, adjacent its lower end, contains two longitudinally spaced pairs of diametrically opposed bars 21. The bars 21 are of thin stock and for convenience in mounting them integral with the stem, are arranged on a diametrical plane. The upper edges of the bars are inclined; their lower edges are transverse to the axis of the stem or preferably somewhat undercut. If, as here shown, the swab element 17 comprises three felt discs 18, the points of the lower pair of bars are spaced from the button 20 by approximately the normal thickness of a disc 18, and the points of the upper pair of bars are spaced a corresponding distance from the points of the lower pair of bars, as indicated in Fig. 3. After assembly in the position of Fig. 3, the washers are compressed downwardly against the head 20 to the position of Fig. 4, where the uppermost pair of bars engages behind the upper surface of the third felt disc 18.

Thus the felt washers are compressed at their centers to approximately two-thirds of their normal thicknesses. The points of the lower set of bars will engage at a mid-point of the intermediate felt disc. The points of the bars keep the discs from rotating on the stem. Rotation of the lowermost disc may further be checked by tooth-like webs 22 in the corner formed by the juncture of the head and stem. For convenience in moulding, these teeth 22 may be co-planar with the bars 21. In addition to engaging the lower face of the first washer to prevent its rotation, they constitute

105
100

110

corner braces to reinforce the head and brace its joint with the stem.

After the felt discs 18 constituting the swab element 17 are thus assembled upon the stem, the 5 opposite end of the stem—which may conveniently be reduced somewhat in diameter—is cemented into the socket or bore 14 of the cap 12 or otherwise suitably secured.

My construction of, and mounting of, the swab element 17 has many advantages. Felt in sheet form is normally compressed across its thickness with the result that the interstices tend to run for the most part in the plane of the sheet. This is even more true in thinner stock than in un- 10 usually thick stock. When the discs 18 are cut from the sheet stock, and then mounted on the stem, the interstices tend to run in a plane at a normal to the axis of the stem and therefore more or less radially. When the washers are in 15 the final position of Fig. 4, the amount of compression is greater near the stem than at the periphery of the swab element 17 as shown in Fig. 4. When the swab is immersed in liquid, the interstices absorb water more or less radially in- 20 wardly rather than longitudinally. Because the longitudinal compression is less at the periphery than near the stem, the greatest amount of liquid will be absorbed near the periphery and less will 25 be absorbed adjacent the stem. In subsequently applying the immersed swab, the liquid preparation will be held for the most part adjacent the swab, where it is most readily transferred.

Each washer is directly engaged by the points of a barb 21 or tooth 22 to prevent its rotation. 30 If the washers were free to rotate, they would prove annoying in applying the preparation and they would also tend to enlarge their center bores until they came off.

The assembling of the swab element 17 on the 40 stem, is, as is apparent, a very simple and inexpensive production step, and one which eliminates the necessity of extra clamping or securing parts. It also avoids the necessity of gluing or cementing the swab onto the stem. Cementing would at 45 best be difficult because of the chemical action of the bottle contents, and would be especially difficult in the use of a plurality of swab discs. The assembly of my swab element 17 on to the stem 16 is so simple that if desired the manufacturer of the preparation may supply extra discs 50 so that the purchaser may renew the swab element after the initial one has become defective. In such case, a simple friction fit or other suitable detachable securing would be substituted 55 for the cementing of the stem to the cap.

When the preparation to be applied is aluminium chloride, as in the present instance, or is of 60 some other formula which is in practice slightly acid, I prefer to mould the stem and cap from an acid-resisting phenol condensation compound such as "Colt Rock" as manufactured by Colt's Patent Firearms Manufacturing Co. of Hartford, Connecticut. The cement used for securing the stem to the cover may then be a "Bakelite" cement of glycerine and litharge, which is not 65 affected by the aluminium chloride.

Another feature of my invention is the material whereof the swab element 17 is made. For 70 use with an aluminium chloride or zinc chloride preparation the felt discs constituting the swab element are of wool. I have found that wool is not attacked by these preparations as is cotton or even silk. Also the wool does not affect the 75 preparation as would sponge rubber which im-

parts an ill smelling sulphurous contamination to these and other preparations.

While I have illustrated and described this specific embodiment of my invention, I contemplate that changes and substitutions may be made therein without departing from the scope and spirit of my invention.

I claim:

1. A swab comprising a supporting stem, a head at the end thereof, a plurality of absorbent washers mounted on the stem, and a barb on the stem over which the washers pass for holding the washers compressed longitudinally of the stem and against the head.

2. A swab comprising a supporting stem and a swab element mounted thereon, the swab element being of compressible absorbent felt and of cylindrical conformation, the swab element being under greater longitudinal compression adjacent its axis than adjacent its periphery, a swab stem comprising a rod shaped body, a head at one end thereof, and barbs projecting from the stem and facing the head for retaining said axial compression.

3. A swab stem comprising a rod, a head at 100 one end of the rod, an integral barb projecting from the rod and facing the head, and a non-integral handle-forming cap attachably secured to the other end.

4. A swab stem comprising a rod, a head at 105 one end formed integrally therewith at one end thereof, an integrally formed barb projecting from the rod a spaced distance from the head, and a tooth radially extending from the rod and integral with the head.

5. A stem for an applicator swab, the stem comprising a rod-like body, a button-like head formed at one end thereof and diametrically opposed barbs extending from the rod-like body a spaced 110 distance from the head and facing the head.

6. A swab stem of moulded material comprising a rod-like body and a button-like head at one end thereof, and an integrally formed tooth the base of which projects from the head and the inner edge of which merges with the rod-like body at 120 an axially spaced distance from the head, for reinforcing the juncture of the head with the body and for preventing the rotation of a cushion-like body pressed against it.

7. A swab comprising a rod-like stem, a head at 125 one end thereof, a plurality of washers of absorbent material mounted on and surrounding the stem and against the head, and means for preventing the rotation of the washers comprising a tooth projecting from the head for engaging the washer which rests against the head and a barb projecting from the rod a spaced distance from the head for engaging another of the washers.

8. A swab comprising a rod-like stem, a head at 130 one end thereof, and a group of washers mounted upon and surrounding the rod, the group comprising three or more washers in contact with each other longitudinally of the stem with one washer in contact with the head and means for holding the washers on the rod and against rotation and under compression longitudinally of the rod, comprising a tooth radially extending from the rod and integral with the head and engaging one of the washers, a barb projecting from the rod and spaced longitudinally from the head for penetrating the face opposite the head of the washer remote from the head.

9. A swab comprising a rod-like stem, a head at 135 one end thereof, and a group of washers mounted 140 upon and surrounding the rod, the group comprising three or more washers in contact with each other longitudinally of the stem with one washer in contact with the head and means for holding the washers on the rod and against rotation and under compression longitudinally of the rod, comprising a tooth radially extending from the rod and integral with the head and engaging one of the washers, a barb projecting from the rod and spaced longitudinally from the head for penetrating the face opposite the head of the washer remote from the head.

10. A swab comprising a rod-like stem, a head at 145 one end thereof, and a group of washers mounted 150

upon and surrounding the rod, the group comprising three or more washers in contact with each other longitudinally of the stem with one washer in contact with the head and means for holding	remote from the head engaging the end face of the washer most remote from the head to hold the washers under compression between said head and said most remote pair of barbs.	
5 the washers on the rod and against rotation and under compression longitudinally of the rod, comprising a tooth radially extending from the rod and integral with the head and engaging one of the washers, a barb projecting from the rod and spaced longitudinally from the head and penetrating the face opposite the head of the washer remote from the head and another barb between the first mentioned barb and the head projecting from the rod and engaging an intermediate washer	11. A cylindrically conformed longitudinally elongated medicant swab comprising a plurality of contiguously, axially and non-rotatably mounted transversely disposed washer-shaped laminations cut from absorbent felt in sheet form wherein the fibers run largely in the general plane of the sheet and with the axes of the washers at a normal to the sheet.	80
10 15 and said remote washer.	12. A cylindrically conformed longitudinally elongated medicant swab comprising a plurality of transversely disposed washer-shaped laminations cut from absorbent felt in sheet form wherein the fibers run largely in the general plane of the sheet and with the axes of the washers at a normal to the sheet, the laminations being axially and non-rotatably mounted and axially compressed together face-to-face with greater compression adjacent their centers than at their peripheries.	85 90 95
